ABSTRACT: The disclosed invention relates to gas flow control valves used by divers wherever a precisely regulated gas mixture volume is required. This regulation is necessary with semiclosed gas or possibly, closed gas breathing systems or systems other than those using demand-type regulators. An inherent requirement of such systems is that a constant volume of gas be precisely valved according to the needs of the diver. In the instant invention this valving is provided by a selective valve unit ensuring any one of several gas-volume combinations to be switched to the valves assembly. In addition, a bypass valve unit is included giving a free flow of gas through the valve mechanism when the diver is descending, working very hard, or when an emergency arises. Construction of the valve mechanism from noncorrosive metals with easily identified controls, enables reliable one-hand operation of the valve mechanism under adverse conditions.

GAS FLOW CONTROL VALVE

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

Divers requiring a constant volume of a particular gas mixture at varying depths are confronted with the problem of being able to provide the proper amount of gas under varying conditions, that is to say, depth and the amount of diver's physical exertion call for different amounts of gas. Existing delicate, elaborate valving mechanisms require a diver's full attention when selecting the proper gas-volume mixture and, thusly detract from the diver's work. In addition, these mechanisms are constructed to operate only within a predetermined range of operations and are not readily modified for service in other situations governed by different physical outputs or depths. At great depths or under poor visibility conditions, a diver additionally is hampered by the fact that visual adjustment is impossible and diving mittens, for protection from the cold of the surrounding water, prevent the diver from determining a particular valve setting.

All the above can result in an adverse psychological impact on the diver that is reflected in the execution of his work assignment.

THE SUMMARY OF THE INVENTION

The present invention is directed to providing a reliable valve mechanism for controlling the volume of gas passed from a diver-carried source of gas, or a remote source, through a semiclosed or closed underwater breathing system. The mechanism includes an essentially rectangularly shaped housing mechanism constructed of a noncorrosive material in which a bypass valve unit is disposed including a traverse duct linking a gas inlet to a gas outlet and a reciprocating piston adapted for selective blocking of the duct thereby permitting no gas flow or a free gas flow in the duct. In addition, a selector valve unit, restricting the gas flow through a traverse passageway separate and distinct from the traverse duct, is provided with a plurality of egress ducts, each containing a threaded screw having an orifice for effectively restricting the volume of transferred gas. The selector valve is rotated to comply with the diver's air-volume demands and the proper amount of gas is passed to the underwater breathing system. A removable plug carried on the housing member allows a rapid changing of the threaded screws having orifices of one size to screws having orifices of different sizes to allow variation of the passed volume of gas as conditions change. Adequate sealing around the bypass valve unit, selector valve unit, and removable plug ensures a transfer of an uncontaminated, constant supply of air through the valve. A large, flat bypass lever actuating the bypass valve unit, a knob-mounted projecting portion, and a detent on the selector valve unit ensure fool-proof operation under the most adverse conditions.

Therefore, it is the prime object of the instant invention to provide a valve mechanism that passes a particular volume of gas.

Another object of the invention is to provide a valve mechanism rugged and foolproof under the most adverse conditions.

Further object of the invention is to provide a valve mechanism readily modified for delivering varying amounts of gas volume depending upon the environmental conditions by means of replaceable orifice members.

Still another object is to provide a valve mechanism so compact and reliable that a diver can operate the mechanism with one hand without substantial detraction from a work assignment.

These and other objects to the invention will become readily apparent from the drawings and ensuing description in which:

FIG. 1 is an isometric depiction of the invention in an operative environment with a sample semiclosed breathing unit worn by a diver;

FIG. 2 is an isometric view of the valve mechanism;

FIG. 3a is a cross-sectional view generally taken along lines 3-3 in FIG. 2 in which the bypass valve unit is closed and blocking gas flow, in addition, the traverse passageway is shown in overlapping relationship to the traverse duct;

FIG. 3b is a cross-sectional view generally taken along lines 3-3 in FIG. 2 in which the bypass valve unit is open and permitting gas free flow plus showing the traverse passageway in an overlapping relationship to the traverse duct;

FIG. 4a is a cross section of the taken along lines 4-4 in FIG. 2 in which the selector valve unit is passing gas through a middle one of the egress ducts;

FIG. 4b is a crosssection of the invention taken along lines 4-4 in FIG. 2 but further emphasizing the position of the port in the gasket as it is rotated from the middle one to a far end one of the egress ducts;

FIG. 4c is a cross-sectional view taken along lines 4-4 in FIG. 2 setting forth the positioning of the port in the gasket on the far one of the egress ducts and the blocking of the other ducts by the gasket;

FIG. 5 sets forth the orientation of the egress ducts in the second cavity;

FIG. 6 is a top view of the gland nut; and

FIG. 7 shows a crosssection of a threaded member.

PREFERRED EMBODIMENT OF THE INVENTION

Referring now to the drawings, FIG. 1 depicts the diver wearing a typical semiclosed circuit underwater breathing apparatus including a pair of breathing bags carried adjacent the chest connected to a CO₂ absorption canister, not shown, supported on the back of the diver. The invention, a gas flow control valve 10, is mounted on a support plate 10a connected on the front of a vest that forms the support for the semiclosed rebreathing circuit. A gas inlet pipe 10b extends to a remotely located constant gas supply source or a back pack supply, not shown for the sake of simplicity in the drawings. An outlet tube 10c passes the proper volume of gas mixtures as determined by the gas flow control valve to the breathing bags at a point between the inhale bag and the canister.

In a preferred embodiment, a housing member 15 is constructed of brass, or a similarly, relatively noncorrosive material, capable of withstanding the abuses and pressure extremes attendant diving operations. The housing member is machined to enclose a bypass valve unit 20, enabling a free flow of gas, and a selector valve unit 30, providing varied volumes of gas through the mechanism. An inlet recess 16 and an outlet recess 17 are formed in the housing member and serves as a gas inlet and a gas outlet for both units. Both recesses are internally threaded in a manner corresponding to the inlet and outlet tubes to facilitate a watertight connection to the rest of the breathing system.

Turning now to FIG. 3a and FIG. 3b, the bypass valve unit is disposed in a first threaded bore 21 in the housing member and a traverse duct 22 extends from the bore to the outlet recesses via the bore. A bypass gland nut 23 is provided having threads corresponding to those tapped within the bore and carries a plurality of sealing "O" rings 23a, 23b, and 23c. Radially extending holes 24 are drilled in the gland nut and are sized and positioned for alignment with the traverse ducts. A bypass valve stem 25, carried in the gland nut, is shaped with a hollow tube-shaped bypass conduit 25b around the shank of the stem and also mounts a sealing ring 25a on an inner section that is forcibly held against the innermost rim of the gland nut by a helical spring 26 mechanically cooperating to function as a biasing element in the bypass valve unit since the mechanical coaction of the helical spring, bypass valve stem,

sealing ring, and gland nut normally blocks any gas flow from the inlet recess to the outlet recess, see FIG. 3a.

A relatively large, flat bypass valve lever 27 extends along substantially one-half of a longitudinal side of the housing member and is secured to the housing member by pin 27a, to rest in contact with the bypass valve stem. Because of its large flat surface, confusion with other elements is minimized. Upon pressing the bypass valve lever with sufficient force to overcome the biasing effect of the helical spring, the bypass valve unit permits a free flow of gas from the inlet recess via the bypass conduit, radially extending holes, and traverse duct, note the gas flow arrows in FIG. 3b. Merely releasing the applied force on the bypass lever allows the helical spring to return the sealing ring to its sealed position against the gland nut to once again block the flow of gas between the inlet and the outlet recess.

The housing member is additionally formed with a bored traverse passageway 49 separate and distinct from the traverse duct that is fed gas through a port 49' in fluid communication with inlet recess 16. The passageway terminates at a traverse passageway outlet 49a in a second cavity 31, and the housing is further formed with a plurality of egress ducts 50a, 50b, and 50c. Selective variation of the gas volume passed therethrough is the function of selector valve unit 30 and includes rotatable and reciprocal selector valve components 30a and gas restricting threaded members 52. The threaded members are screwed into the ducts and the transfer of gas to a third cavity, threaded bore 51.

A selector gland collar 32 is force-fitted or brazed inside the entrance to the second cavity and a selector gland nut 33 mounting "O" ring seals 33' and 33'', is screwed into the collar. Four, relatively deep, curved recesses 33a, 33b, 33c, and 33d are formed on the nut's outer surface in a 90° spaced relationship and ball-rider surfaces 34a, 34b, 34c, and 34d are interposed between the curved recesses, the purpose of which will be pointed out below.

A valve piston 35 extends through the gland nut to the interior of the second cavity and terminates in a dishlike gas channeling portion 36. The channeling portion is shaped with a single laterally extending bored channel 37, being in communication with a single inwardly, longitudinally-extending throat 38 and a pair of oppositely disposed holes 38a and 38b (for pressure equalization inside the mechanism). Adjacent the inwardmost side of the channeling portion, a neoprene gasket 39 is carried having a lateral gasket port 40 disposed in a coincident relationship with respect to throat 38.

At the upward end of the valve piston an indicator knob 41, mounting a projecting portion 41a, is brazed or screwed onto the piston. On its inner surface the knob is provided a pair of cup-shaped chambers spaced 180° apart for containing a pair of detent balls 42 and 43. A second helically-shaped biasing spring 35a is wound around the valve piston and is constructed to force the indicator knob toward the selector gland nut to securely position the moveable selector valve components in position when the detent balls rest in the curved recesses, that is to say, the moveable components are biased to remain in one of four positions spaced 90° from one another.

The knob is rotated, the detent balls ride out of the curved recesses and onto the ball rider surfaces arcuately disposed between the recesses, see FIG. 4b. The ball's riding out of the recesses axially overcomes the biasing spring and displaces the valve piston to raise the gasket port from a particular egress duct. When the balls fall into adjacent arcuately disposed curved recesses, with an audible "snap" and an impulse heard and felt by a diver, the gasket port and aligned throat are placed immediately adjacent another one of the egress ducts. The "snap" and projecting portion 41a positively indicate to a diver that a desired valve position providing a gas transfer rate has been selected. By noting FIGS. 4a, 4b, and 4c this transfer can be seen for the changing of gas flow communication from egress duct 50b to 50c, the knob being turned in a counter-clockwise direction.

The egress ducts, 50a, 50b, and 50c, terminate at their innermost end adjacent gasket 39 in the configuration of FIG. 5. A blank space 50d is provided to enable the operator to shut off the selector valve unit by rotating the gasket port to a position adjacent the blank space via the selector knob. As mentioned before, at the other end of the three ducts are located three separate threaded members 52, each enclosing an axial orifice of different diameter in communication with a third cavity 51. The diameters are different from one another to allow only a predetermined amount of gas to pass therethrough, the amount being determined by the particular diameter, the pressure of the external source of gas, and the surrounding pressure.

The third cavity is closed and sealed by a plug 53 to form a mixing chamber 54. From a mixing chamber the chamber passageway 54a links the outlet recess to the inlet recess via the traverse passageway, selector valve unit, egress ducts, and mixing chamber.

FIGS. 4a, 4b, and 4c, show the transfer of gas from the traverse passage outlet 49a through the moveable selector components, egress ducts, threaded members, and to the outlet recess. The flow arrows in FIG. 4a show a transfer of a first volume of gas through egress duct 50b and its associated threaded member while FIG. 4b, depicts the axially displaced position of the moveable selector valve components as the knob is rotated counterclockwise and balls 42 and 43 are carried on ball-rider surfaces 34a and 34c respectively. The gasket port 40 has been pulled away from egress duct 50b and is positioned arcuately midway between egress ducts 50b and 50c. Unimpeded flow through all the ducts now prevails, but, since switching time is relatively short, this matters little.

FIG. 4c shows the gasket port adjacent egress duct 50c, with the gasket again sealing off the other ducts to allow only a measured amount of gas to flow through duct 50c.

Noting FIG. 1, operation of the invention is easily performed by a diver when a changed supply of gas is needed. As shown in the drawings, the diver need only raise his left hand to the gas flow control valve and press the bypass lever to effect the mechanical coaction shown in FIG. 3b to permit a free flow of gas through the mechanism. A free flow of gas may be necessary under strenuous diving working conditions or if the diver is descending relatively rapidly.

Precise lesser volumes of gas are delivered to the diver by merely turning the indicator knob without undue distraction. As explained above, turning of the knob will align the gasket port with a desired egress duct containing a particular threaded member to deliver the correct amount of gas. The projecting portion 41a enables the diver to know the selector valve unit's position without having to look at the valve mechanism and the position of the mechanism can be determined even while wearing heavy diving mittens.

When diving at depths, loss of visibility and extreme cold imposes limitations on a diver's ability to carry out assigned tasks. Heavy insulating mittens, while affording some relief from the cold, further diminish a diver's sense of touch to the extent that selection of a proper small knob or switching position is impossible. The present invention compensates for visibility and sensory limitations by providing a relatively large bypass lever and a single, unmistakable rotatable selector knob, both easily identifiable and arranged for single hand operation. As the selector valve knob is rotated, the detent balls ride out of one set of curved recesses and "snap" into another set to further apprise a diver of the proper selector valve setting. Thusly, the invention provides an improvement over existing diving valve mechanisms ensuring a reliability heretofore unobtainable.

Modifications can be made in view of the above teachings within the scope of one skilled in the art, and the disclosed inventive concept is to be construed as taken to include such modifications and not to be interpreted as applying to only specific embodiment set out above.

I claim:

1. A diver's gas flow valve mechanism for ensuring reliable single hand control of the volume of gas passed therethrough under adverse conditions comprising:
  - a housing member having a gas inlet recess, and a gas outlet recess, a first cavity, and a second cavity;
  - a bypass valve unit disposed in said first cavity including; a traverse duct linking said inlet recess to said outlet recess; reciprocating means carried in said first cavity having an element configured to normally block said traverse duct; a hinged bypass valve lever longitudinally extending along a substantial portion of said housing member being sized and positioned to ensure a single handed displacement of said reciprocating means and said element to selectively enable a free flow of said gas through said traverse duct;
  - a selector valve unit disposed in said housing member including;
  - a traverse passageway linking said inlet recess to said second cavity;
  - a plurality of egress ducts each adapted to allow different rates of flow of said gas therethrough linking said second cavity to said outlet recess;
  - an axial valve piston extending from said second cavity to the exterior of said housing member mounting on its inner end a disk-shaped gasket having a lateral gasket port formed to ensure gas flow communication from said second cavity to said outlet recess upon being aligned with a single one of said egress ducts; and
  - means for simultaneously imparting axially reciprocal motion and rotational motion to said valve piston to axially displace and rotationally position said gasket port in realinement with a selectively different one of said egress ducts to ensure a different rate of said gas flow communication, both said bypass valve unit and said selector valve

35

unit are further provided with external portions configured and oriented to ensure reliable one handed operation under adverse conditions.

2. A valve mechanism according to claim 1 further including means for limiting the volume of said gas passed through each of said egress ducts being disposed therein and each having different sized orifices.
3. A valve mechanism according to claim 2 in which the means for imparting simultaneous axially reciprocal motion and rotational motion includes a helical biasing spring axially disposed about the axial valve piston and an indicator knob carrying ball members opposed to arcuately disposed curved recesses to impart said reciprocal motion upon being rotated, upon said realinement, snapping said gasket port in said gas flow communication with a different one of said egress ducts.
4. A valve mechanism according to claim 3 further including a third cavity formed in said housing member and linking said egress ducts to said gas outlet recess, the limiting means having their outer surfaces exposed therein and a removable plug closing said third cavity for permitting exposure of said limiting means and the selective installation and removal thereof.
5. A valve mechanism according to claim 4 further including biasing means provided in said bypass valve unit urging said bypass valve unit to normally block said traverse duct.
6. A valve mechanism according to claim 5 further including means carried on an outer side of the means for simultaneously imparting axially reciprocal motion and rotational motion for indicating the relative alignment and said realinement within said selector valve unit.
7. A valve mechanism according to claim 6 in which said housing member is essentially rectangular shaped and the first, second, and third cavities are lateral bores.
